J. E. WILLOUGHBY

DRAFT FAN

Filed March 16, 1925

FIG. 2

Inventor
James E. Willoughby.

By *Herbert E. Smith*
Attorney

UNITED STATES PATENT OFFICE.

JAMES E. WILLOUGHBY, OF KELLOGG, IDAHO.

DRAFT FAN.

Application filed March 16, 1925. Serial No. 15,878.

To all whom it may concern:

Be it known that I, JAMES E. WILLOUGHBY, a citizen of the United States, residing at Kellogg, in Shoshone County 5 and State of Idaho, have invented certain new and useful Improvements in Draft Fans, of which the following is a specification.

My present invention relates to improvements in draft fans adapted especially for use in the ventilation of buildings, as dwellings. The fan is designed for use in connection with a smoke flue or pipe from a heating stove, furnace, or other appliance, and 10 is actuated by means of passing currents of smoke, gas or air from the fire, to drive a ventilating fan located exterior of the smoke flue. The ventilating fan is arranged in position to create a circulation of air in the 15 room through which the smoke flue passes, by driving from the smoke flue the air warmed or heated by radiation from the smoke flue and thus inducing flow of currents of air to and from the smoke flue to 20 be heated from the exterior thereof.

In carrying out my invention I utilize means within the smoke flue for directing or guiding the upwardly flowing currents of air or gases to the motor fans within the smoke 25 flue to insure greatest efficiency for the motor fans and yet provide ample space for the unimpeded movement of the draft from the fire. Means are also provided for journaling the motor spindle in such manner that wear 30 of parts may readily be compensated for and the rotating spindle provided with bearings forming a minimum frictional resistance to 35 the operation of the device by natural draft.

The invention consists in certain novel 40 combinations and arrangements of parts as will hereinafter be more fully set forth and claimed.

In the accompanying drawings I have 45 illustrated one complete example of the physical embodiment of my invention wherein the parts are combined and arranged in accordance with the best mode I have thus far devised for the practical application of the principles of my invention.

Figure 1 is a view in elevation showing 50 the appliance of my invention operatively located in a section of a smoke flue.

Figure 2 is a vertical sectional view at

right angles to that of Figure 1, on line 2—2 of Figure 1. 55

Figure 3 is an enlarged detail view of the spindle with its bearings in section.

In the preferred form of my invention I utilize a section of a smoke pipe 1, adapted to receive and convey smoke or gases and 60 air from a heating or other type of stove or furnace, which flue it will be understood is heated from the interior by hot gases of combustion and radiates heat from its exterior to the room or space in which the flue 65 is located.

Within the cylindrical flue I arrange a vertical or longitudinally extending shield 70 preferably made up of sheet metal fashioned to proper shape and secured as by rivets at the top and bottom ends to the smoke flue. This shield is fashioned with a pair of parallel concave deflecting faces 2 and 3 which extend upwardly and curve laterally 75 from one side of the smoke flue toward its longitudinal or vertical center as seen in Figure 2.

At their upper ends these deflecting faces terminate in reversely curved concave faces 4 and 5 which return to the wall of the 80 smoke flue in line with the fixed bottom end of the shield.

As an auxiliary means for providing an unobstructed or unimpeded flow of the gases of combustion from the furnace through the 85 smoke flue, the shield is slotted as at 6 to afford a space, in addition to the spaces at the edges of the shield, for upward draft through the flue.

Within the smoke flue and arranged transversely thereof are a pair of spaced motor fans 7 and 8, each alined with a deflecting face 2 and 3, and fixed by set screws or bolts 9 on the spindle 10. 90

The spindle is journaled transversely of 95 the smoke flue and passes therethrough with bearings at its ends, which ends are fashioned with cone journals 11 and 12, the former being engaged within a shield sleeve 13, against a fixed bearing block 14. The 100 bearing block is supported exterior of the smoke flue and a suitable distance therefrom on the bracket 15 which is affixed for support on the exterior of the smoke flue.

The cone journal 12 has a bearing against 105 a resiliently supported bearing block 16

which is encased within a hollow bearing sleeve 17 attached by its flanges 18 and bolts 19 to the smoke flue. A shield sleeve 20 integral with the bearing sleeve 17 projects within the smoke flue and over the end 12 of the spindle as a shield therefor.

By means of a spring 21 located in the fixed bearing sleeve 17 and interposed between the adjustable bearing block 16 and 10 an adjusting bolt 22 in the open end of the bearing sleeve 17, the bearing block 16 is urged into close bearing contact with the cone journal 12 to support the spindle.

By this arrangement of parts a minimum 15 frictional resistance is obtained between the cone journals and their bearings for the rotary spindle, and the resiliently supported bearing block 16 may be adjusted as required to take up wear and regulate the frictional resistance.

On the spindle exterior of the smoke flue and located between a gasket 23 of the flue and the bearing block 14, is an impeller fan 24 secured on the spindle in adjusted position 25 by means of a set screw 25 in the hub 26 of the fan.

The impeller fan is located adjacent to the smoke flue and is revolved or rotated 30 from the motor fans through the spindle as the gases of combustion pass upwardly through the smoke flue and are directed by the deflectors to the motor fans.

It will be apparent that as the heat is 35 radiated from the exterior of the smoke flue the impeller fan will drive the warm air from the flue, thus causing a circulation of air in the room, the air flowing in currents by induction to the fan and being impelled therefrom by the action of the fan for ventilation of the room.

Having thus fully described my invention, what I claim as new and desire to secure by Letters Patent is:

1. The combination with a smoke flue having a slotted shield therein forming a pair of deflector plates for updraft through the flue, of a spindle supported transversely of the smoke flue and having an exterior impeller fan thereon, and a pair of fans within the flue aligned with the deflector plates for 45 operating the impeller fan.

2. The combination with a smoke flue having a shield with a central longitudinal slot therein forming a pair of concave deflector plates extending laterally from the inner wall of the flue and terminating in reversely curved concave faces, of a spindle supported transversely of the smoke flue and an exterior impeller fan thereon, and a pair of fans within the flue aligned with 55 60 said deflector plates for operating the impeller fan.

3. The combination with a conduit adapted for the passage of heated gases therethrough, of a bracket supported on said conduit externally thereof, a bearing rigidly carried in said bracket, a spring pressed bearing disposed through a wall of said conduit at a point diametrically opposite the first named bearing, a spindle rotatably mounted in said bearings and extending through and beyond said conduit, impeller blades rigidly secured to said spindle internally of said conduit, means in said conduit for directing the heated gases against 70 75 said blades for rotating said spindles, and a driven member carried by said spindle externally of the conduit.

In testimony whereof I affix my signature.
JAMES E. WILLOUGHBY.
